PORTABLE ELECTRIC BARBECUE GRILL

Merlin W. Ehrlichmann, Minnetonka, Minn., assignor to West Creek Co., Inc., Minnetonka, Minn.

Filed Mar. 26, 1970, Ser. No. 22,063

Term of patent 14 years

Int. Cl. D7—04

U.S. Cl. D81—10

FIG. 1 is a perspective view of a portable electric barbecue grill embodying my new design;

FIG. 2 is a top plan view thereof;

FIG. 3 is a side elevational view thereof;

FIG. 4 is a bottom plan view thereof; and

FIG. 5 is a sectional view thereof taken as on line 5—5 in FIG. 2.

I claim:

The ornamental design for a portable electric barbecue grill, substantially as shown.
